LINE FAULT INDICATING SYSTEM

James S. Astin, Pittsburgh, Pa., assignor to Westinghouse Electric Corporation, East Pittsburgh, Pa., a corporation of Pennsylvania

Application December 29, 1945, Serial No. 638,360

2 Claims. (Cl. 177—311)

1

My invention relates, generally, to indicating systems and, more particularly, to alarm systems for indicating a grounded phase of a three-phase power system.

On a three-phase ungrounded power system, it is often desirable to provide some method of indicating when a phase accidentally becomes grounded. One method which has been utilized is to connect the actuating coil of a voltage relay in the broken delta on the secondary side of potential transformers which are Y-connected on the primary side with their neutral grounded. When a phase becomes grounded, voltage is developed across the coil of the relay which closes its contact members and sounds an alarm.

Since it usually requires considerable time to locate and remove the ground, it is desirable to be able to silence the alarm and yet leave the circuit in such condition that a subsequent ground on any other bus section will again sound the alarm. One of the objects of my invention is to provide an indicating system capable of performing the foregoing function.

Another object of my invention is to provide a ground indicating system which is automatically restored to normal after the ground is cleared.

A further object of my invention is to provide a ground indicating system which may be utilized with one or a plurality of sections of a power system.

A more general object of my invention is to provide a ground indicating system which shall be simple and efficient in operation and which may be economically manufactured and installed.

Other objects of my invention will be explained fully hereinafter or will be apparent to those skilled in the art.

In accordance with one embodiment of my invention, relays are so connected to potential transformers that an alarm is sounded when a ground occurs on any one of the conductors of a plurality of sets of conductors and a visual indication of which conductor is grounded is provided. The alarm may be silenced without turning off the visual indication and subsequent grounds on any other set of power conductors will sound the alarm.

For a fuller understanding of the nature and objects of my invention, reference may be had to the following detailed description, taken in conjunction with the accompanying drawing, in which the single figure is a diagrammatic view of an indicating system embodying the principal features of my invention.

Referring to the drawing, the indicating sys-

2

tem shown therein is suitable for indicating a ground on either one, or both, of a pair of three-phase bus sections designated as bus section 1 and bus section 2. It will be understood that the system may be utilized with any desired number of bus sections or sets of power conductors by providing additional apparatus similar to that illustrated.

The apparatus required for bus section 1 comprises a set of potential transformers PT1. A voltage relay V1, an auxiliary relay VX1, a push-button switch PB1, indicating lamps 1, 2, 3, XL1 and L1 and an alarm A which may be a buzzer or bell or other suitable signalling device.

The apparatus for the bus section 2 is similar to that for the bus section 1 and comprises a set of potential transformers PT2, a voltage relay V2, an auxiliary relay VX2, a push-button switch PB2 and indicating lamps 21, 22, 23, XL2 and L2. The alarm device A is common for both bus sections and need not be duplicated.

As shown, the primary windings of the potential transformers PT1 are Y-connected to the power conductors of bus section 1, the neutral of the Y-connected transformers being grounded. The secondary windings of the potential transformers are delta-connected with the actuating coil of the voltage relay V1 connected in the broken delta through normally closed contact members 11 of the auxiliary relay VX1. The indicating lamps 1, 2 and 3 are so connected across the secondary windings for phases 1, 2 and 3 that the three lamps burn with equal brilliance under normal conditions. However, when a ground occurs on one of the phases, the lamp corresponding to that phase becomes dark, while the remaining two burn with increased brilliance, thereby providing an indication of which phase is grounded.

Furthermore, when a ground occurs on any phase, the actuating coil of the relay V1 becomes energized, thereby closing its contact members to energize the alarm device A. The operator can tell which bus section and which phase of the

bus section is grounded by noting the condition of the lamps 1, 2 and 3. The alarm device A may be silenced by closing the push button PB1, thereby energizing the actuating coil of the auxiliary relay VX1 which opens its contact members 11 to deenergize the relay V1, which, in turn, opens its contact members to deenergize the alarm device A. A holding circuit is provided for the actuating coil of the relay VX1 through its contact members 12 which are closed when the actuat-

ing coil of the relay is energized.

When the ground is finally removed from the power conductor, the voltage across the broken delta of the secondary windings of the potential transformers disappears, thereby deenergizing the auxiliary relay VX_1 which returns to its original position. If a ground occurs on another bus section, such as bus section 2, before the auxiliary relay VX_1 is deenergized, the alarm A will be sounded by the operation of the relay V_2 in a manner similar to the operation of the relay V_1 on the bus section 1.

The alarm A may be silenced by closing the push-button switch PB_2 which causes the operation of the relay VX_2 in the same manner as the relay VX_1 . Likewise, a ground occurring on any other bus section provided with the indicating apparatus will cause the operation of the alarm device A.

If it is desired to provide a visual indication at some remote point as to which bus section is grounded after the alarm device has been silenced, the indicating lamp L_1 may be energized through contact members 13 of the auxiliary relay VX_1 , or the indicating lamp XL_1 may be connected in parallel-circuit relation with the actuating coil of the auxiliary relay VX_1 in the manner shown. If desired, both lamps may be utilized and located at two different points. These lamps will continue to burn until the ground is removed from the power conductor. Thus, by providing similar lamps for each bus section, visual indications of the condition of each bus section may be provided at any desired location.

From the foregoing description, it is apparent that I have provided a system suitable for indicating a ground on any power conductor of a plurality of sets of power conductors, and for identifying the particular power conductor involved. The system permits the signalling or alarm device to be silenced without a loss of indication that the ground has occurred, and without loss of identification of the particular power conductor.

Furthermore, subsequent grounds will operate the alarm device regardless of whether or not the first ground has been cleared. The system is automatically restored to normal upon the clearance of the ground, without depending upon the operator to reset the apparatus.

Since numerous changes may be made in the above-described construction and different embodiments of the invention may be made without

departing from the spirit and scope thereof, it is intended that all matter contained in the foregoing description or shown in the accompanying drawing shall be considered as illustrative and not in a limiting sense.

I claim as my invention:

1. In an indicating system, in combination, a set of three-phase power conductors, potential transformers having primary windings connected to said power conductors, a voltage relay having an actuating coil connected to the secondary windings of said transformers to be responsive to a ground on one of said power conductors, an alarm device energized through the contact members of said relay, an auxiliary relay for controlling the operation of said voltage relay, manually operable means for controlling the energization of said auxiliary relay by said potential transformers, and contact members on said auxiliary relay for establishing a holding circuit for the auxiliary relay, said holding circuit being deenergized by the removal of the ground from said power conductor.
2. In an indicating system, in combination, a plurality of sets of three-phase power conductors, a set of potential transformers for each set of power conductors, said transformers having primary windings connected to the power conductors, a voltage relay for each set of transformers, said relays having their actuating coils connected to the secondary windings of said transformers to be responsive to grounds on the power conductors, an alarm device energized through the contact members of said relays, an auxiliary relay for controlling the operation of each voltage relay, manually operable means for controlling the energization of each auxiliary relay, and holding means for each auxiliary relay, said relays being automatically deenergized by the removal of the ground from their respective power conductors.
